US00D895811S

(12) **United States Design Patent** (10) Patent No.: **US D895,811 S**
(45) Date of Patent: ** Sep. 8, 2020

(54) **EAR-MOUNTABLE BIO-SENSOR DEVICE**

(71) Applicant: **Inova Design Solutions Ltd**, London (GB)

(72) Inventors: **Steven Green**, Oxon (GB); **Leon Marsh**, London (GB); **Emily McLoughlin**, West Sussex (GB)

(73) Assignee: **Inova Design Solutions Ltd**, London (GB)

(**) Term: **15 Years**

(21) Appl. No.: **29/691,702**

(22) Filed: **May 17, 2019**

CLAIM

The ornamental design for an ear-mountable bio-sensor device, as shown and described.

DESCRIPTION

FIG. 1 is a rear perspective view of an ear-mountable bio-sensor device showing our new design;

FIG. 2 is a front perspective view thereof;

FIG. 3 is a side view thereof;

FIG. 4 is another side view thereof;

FIG. 5 is a rear view thereof;

FIG. 6 is a front view thereof;

FIG. 7 is a top view thereof; and,

FIG. 8 is a bottom view thereof.

The broken line showing represents an environmental subject matter that forms no part of the claimed design.

1 Claim, 8 Drawing Sheets
